UNITED STATES PATENT OFFICE.

HANS O. OPSAL, OF RACINE, WISCONSIN.

SASH-BALANCE.

SPECIFICATION forming part of Letters Patent No. 269,104, dated December 12, 1882.

Application filed September 16, 1882. (No model.)

To all whom it may concern:

Be it known that I, HANS O. OPSAL, of Racine, in the county of Racine and State of Wisconsin, have invented certain new and useful 5 Improvements in Sash-Balances; and I do hereby declare that the following is a full, clear, and exact description of the invention, which will enable others skilled in the art to which it appertains to make and use the same, reference being had to the accompanying drawings, which form a part of this specification, and in which—

Figure 1 is a front elevation of a window-frame provided with my improved sash-balance. Fig. 2 is a perspective view of one of the balances with its appurtenances. Fig. 3 is a cross-section through the window-frame and balance.

Similar letters of reference indicate corresponding parts in all the figures.

My invention has relation to that class of sash-balances in which the sash-cord runs over helical pulleys actuated by springs of the same construction as watch and clock springs, 25 said springs counterbalancing the weight of the window-sashes; and it consists in the detailed construction of the same, as hereinafter more fully described and claimed.

In the accompanying drawings, the letter 30 A represents the window frame or casing, and B B the two sashes. In the upper end of the two jambs, or on the lintel or upper part of the frame, are fastened by screws or other means two plates, C C, one on each side of 35 the frame. On the outside of these plates, extending into the reveal or open space between the frame and the wall, are two brackets, c c, forming rigid bearings for the axle d, on which turn the spring-barrels D D, and 40 their conical helices or helical pulleys D' D'. The spring-barrels D D are of the usual construction, having the inner end of their spiral springs fastened to the rigid axle d, and have the conical helical pulleys D' D' rigidly fixed 45 on them, over which the sash cord or wire F runs. Their springs must be of sufficient strength to counterbalance the weight of the sash and window-glass, and are wound up when they are put in place by turning the 50 spring-barrel, the axle being rigidly fastened in its bearings, and when the spring is wound holding it fast till the sash-cord is fastened

to the sash by means of a screw, g, passing through plate C, and through a screw-threaded collar, g', so as to bear with its inner end when 55 screwed up against the rim of the spring-barrel, which can be released after the cord has been fastened, thus allowing the spring to act. The sash-cords pass through transverse slots h in plates C, and over guide-pulleys i, sliding 60 on bars j, which are fastened in both ends in brackets m on the plate C, said slots and pulleys serving to guide the cords into the helical grooves of the conical pulleys D' by the pulleys i sliding on the bar j, so as to be immediately opposite that part of the helical groove where the cord is, thus preventing the cord 65 from slipping out of the groove and the apparatus from getting out of order. The plates C are bent to form channels or recesses, as 70 shown at k, for the insertion of the cleats separating the ways in which the sashes slide.

This device, while chiefly intended for a sash-balance, is also applicable to other purposes, and may be used, for example, for a lamp-balance, the lamp simply taking the place of the sash, a suitable support being provided for the attachment of the spring-barrel and its appurtenances, which together constitute the 75 complete balance.

Having thus described my invention, I claim and desire to secure by Letters Patent of the United States—

1. In a sash spring-balance, the hollow screw-threaded sleeve g', having screw g, adapted to 85 be brought to bear against the rim of the spring-barrel and hold it, substantially as and for the purpose shown and set forth.

2. In a sash spring-balance, the combination of plate C, slotted at h, and having fixed arms 90 or bearings c c, axle d, spring-barrels D, provided with the conical helical pulleys D', sliding guide-pulleys i, and sash cord or wire F, all constructed and arranged to operate substantially in the manner and for the purpose 95 herein shown and set forth.

In testimony that I claim the foregoing as my own I have hereunto affixed my signature in presence of two witnesses.

HANS O. OPSAL.

Witnesses:

NILS ANDERSEN,
JOHN B. WINSLOW.
